UNITED STATES PATENT OFFICE.

FREDERICK J. ZIMMERER, JR., OF MIDDLETOWN, CONNECTICUT, ASSIGNOR TO THE RUSSELL MANUFACTURING COMPANY, OF MIDDLETOWN, CONNECTICUT, A CORPORATION OF CONNECTICUT.

DESIGN FOR AN ELASTIC FABRIC.

Application filed November 20, 1926. Serial No. 19,799. Term of patent 14 years.

To all whom it may concern:

Be it known that I, FREDERICK J. ZIMMERER, Jr., a citizen of the United States, residing at Middletown, in the county of Middlesex and State of Connecticut, have invented a new, original, and ornamental Design for Elastic Fabrics, of which the following is a specification, reference being had to the accompanying drawing, forming part thereof, in which the figure is a plan view of an elastic fabric, showing my new design.

The design comprises alternating stripes of a solid rib and a rib having a mottled effect or appearance, the latter being comparatively wide and prominent in contrast with

the former. These wide mottled and the narrow stripes are crossed at regular intervals with other stripes imparting to the fabric a sort of plaid effect and this combination of the wide and mottled stripes and the crosswise stripes to create this plaid effect forms a distinguishing feature of the design. The detailed illustration of the body of the selvage at the upper edge of the fabric appears also at the lower edge forming the width of the elastic fabric.

I claim:—

The ornamental design for an elastic fabric, as shown and described.

FREDERICK J. ZIMMERER, JR.
